(57) **CLAIM**

The ornamental design for a diaphragm pump, as shown and described.

DESCRIPTION

1. Diaphragm pump
- 1.1 : Front
- 1.2 : Back
- 1.3 : Right
- 1.4 : Left
- 1.5 : Top
- 1.6 : Bottom
- 1.7 : Perspective
- 1.8 : Perspective

1 Claim, 8 Drawing Sheets(56)
